Primary Examiner—Jeffrey Asch
Attorney, Agent, or Firm—Kokjer, Kircher, Bowman & Johnson[57] **CLAIM**

The ornamental design for a portable handheld combination GPS and communication transceiver, as shown and described.

DESCRIPTION

FIG. 1 is a perspective view of a portable handheld combination GPS & communication transceiver according to the present invention;

FIG. 2 is a front elevation view thereof;

FIG. 3 is a left side elevation of FIG. 2 thereof;

FIG. 4 is a right side elevation of FIG. 2 thereof;

FIG. 5 is a rear elevation thereof;

FIG. 6 is a top plan view thereof; and,

FIG. 7 is a bottom plan view thereof.
